UNITED STATES PATENT OFFICE.

CHARLES E. WEHN, OF LOS ANGELES, CALIFORNIA.

COLLAPSIBLE TABLE.

SPECIFICATION forming part of Letters Patent No. 737,805, dated September 1, 1903.

Application filed May 22, 1902. Serial No. 108,592. (No model.)

To all whom it may concern:

Be it known that I, CHARLES E. WEHN, a citizen of the United States, residing at Los Angeles, in the county of Los Angeles and State 5 of California, have invented a new and useful Collapsible Table, of which the following is a specification.

This invention relates to tables, and particularly to those constructed to be collapsed; 10 and some of the objects of the invention are to provide an article of this character which is simple and cheap in construction and at the same time suitable for the purpose intended.

It is also an object of this invention to provide a table capable of general use when extended and adapted to be reduced in size and serve the purpose of a small table or stand, thereby occupying less space.

Another object of the invention is to provide a table capable when collapsed of retaining articles or vessels which are used when the table is in the extended or expanded position.

Furthermore, an object of this invention is to provide mechanism for operating the parts 25 and for retaining the parts in operative position.

With these and other objects in view the invention consists, essentially, in the construction, combination, and arrangement of parts substantially as more fully described in the following specification and illustrated in the accompanying drawings, forming part of this application, in which—

Figure 1 is a top plan view of the table in a collapsed position. Fig. 2 is a similar view of the same, showing the sliding leaves extended. Fig. 3 is a top plan view of the table, illustrating the sliding leaves extended and the folding leaves opened outwardly. Fig. 4 illustrates details of construction. Fig. 5 is a sectional view taken on line 5 5 of Fig. 2, illustrating the invention on an enlarged scale; and Fig. 6 is a detail view of the mechanism for locking the depressible center.

Similar characters of reference designate corresponding parts throughout the several views.

Referring to the drawings, the reference character 1 designates legs or supports, which 50 may be of any preferred form and the upper part whereof is preferably inclosed, as at 2, and cross-pieces 3 may be secured between

the legs, while upon the outside of the inclosing material 2, upon two sides of the legs, are preferably secured guide-pieces 4, having 55 internal longitudinal recesses or grooves 5 to receive the arms or extensions 6 and 7, formed on or connected with the sliding leaves or sections 9, substantially as shown in Figs. 2 and 5 of the drawings. By means of this construction the sliding leaves 9 may be forced together into the position shown in Fig. 1 or may be drawn apart, as illustrated in Figs. 2 and 3 thereof.

Hinged upon the inside of the cross-pieces 65 3 are folding leaves or sections 10, constructed to fold outwardly over and rest upon the pieces 3, Fig. 3, and the folding leaves 10 are preferably provided with engaging devices 11, Fig. 2, to engage eyes or other devices 12 upon the 70 sliding leaves 9 to retain the sliding and folding leaves against each other and in the same plane to prevent unevenness in the several parts of the table-surface, and guiding-tubes 13 are secured upon the respective legs 1 by 75 means of clamps 14 or in any other manner, and within said tubes are mounted plungers 15, preferably having screw-threaded extremities to removably engage attaching-plates 16 upon the cleats 17, attached to the under side 80 of the center piece 18 of the table, said cleats being constructed to bear against the inner face of the opposite legs of the table to afford additional means for guiding the depressible center piece of the table.

The legs 1 are preferably provided with a longitudinal recess 19 to receive weights 20, attached to cords or chains 21, passing over antifriction devices 22, mounted in the upper end of each of the legs and attached to 90 the cleats 17 to afford means for elevating the center piece 18 of the table, which is guided by the plungers or rods 15 and the cleats 17, as before explained.

If found desirable in practice, the counter-weighted cords and antifriction devices may be dispensed with, and strong spiral springs 22 may be mounted in the bottom of the tubes 13 to force the plungers 15 upwardly and elevate the center piece of the table, and short coil-springs are preferably located in the bottom of the tubes 13 to act as cushions or bumpers for the plungers upon the depression of the center piece.

- Mounted in a hanger 23, secured upon the under side of the center piece 18, is a rod or rock-shaft 24, carrying cross-pieces or T-heads 25, connected with pull-rods 26 and 27, attached 5 to spring-actuated catches 28, constructed to engage sockets 29, formed in or secured to the cross-pieces 3, Fig. 5 of the drawings, when the center piece is elevated into the plane of the sliding leaves, as will be readily understood.
- The operation of this invention will be readily understood from the foregoing description, when taken in connection with the accompanying drawings and the following explanation 15 thereof. Assuming that the table is in the collapsed or contracted position shown in Fig. 1 of the drawings, the first step is to pull apart or separate the sliding leaves 9 until the same extend beyond the frame of the 20 table, whereupon the folding leaves 10, Fig. 2, are then opened outwardly and the center piece is elevated and locked, after which the sliding leaves are forced together or against the center piece and folding leaves and fastened to the latter, as shown in Fig. 3 of the 25 drawings, in which position the table is ready for use in its extended or expanded position. If the table is used as a dining-table and it is desired to leave the table-cloth, the center-piece, the salt and pepper shakers, and such articles upon the table until the next meal, then it is only necessary to deposit the same upon the center piece of the table and fold the table-cloth thereon, then disconnect 30 or disengage the sliding and folding leaves, and pull one sliding leaf out until sufficient room is accorded to operate the oscillating or rocking bar 24 to release the spring catches or plungers 28, whereupon the center piece, 35 with the articles thereon, may be forced downwardly and the folding leaves folded there-over into the position shown in Fig. 2, after which the sliding leaves may be forced together into the position shown in Fig. 1, in 40 which position the table will occupy but little space and may be utilized temporarily as a stand for various purposes.
- It is not desired to confine this invention to the specific construction, combination, and 45 arrangement of parts herein shown and described, and the right is reserved to make all such changes in and modification of the same as come within the spirit and scope of the invention.
- 55 I claim—
1. A table provided with a frame, a depressible center within said frame and leaves hinged upon the interior of the frame and constructed to fold within said frame over said center 60 when the latter is depressed.
2. A table provided with a frame, a depressible center mounted within said frame, leaves hinged to the interior of said frame constructed to fold above said center when the latter
- is depressed, and separate leaves supported 65 in said frame and constructed to cover said hinged leaves and center when in said position.
3. A table provided with a depressible center, leaves hinged to the interior of said frame and constructed to fold over said center and within said frame when said center is depressed and leaves having extensions slidably mounted in grooves in said frame, whereby the latter leaves may be forced together above 70 said hinged leaves and center.
4. A table provided with a counterweighted central portion, folding leaves hinged there-above and constructed to fold thereover when said center is depressed and sliding leaves on 80 each side of said center and movable longitudinally of said folding leaves.
5. A table provided with a frame, counterweighted center mounted therein, leaves hinged upon the interior of said frame and 85 constructed to fold over said center when the latter is depressed, and leaves supported in said frame constructed to slide together over said hinged leaves and center when the same are in said position. 90
6. A table provided with recessed legs, counterweights mounted in said recesses, guides upon said legs, a depressible center connected with said counterweights and carrying plungers working in said guides and 95 leaves mounted in said frame and constructed to slide together over said center when the latter is depressed.
7. A table provided with recessed legs having antifriction devices, a depressible center 100 portion, means connected therewith and with said weights and passing over said devices to support said center portion, folding leaves at the ends of the said portion, sliding leaves at the ends of the folding leaves, and means for 105 locking said center portion in such position as to form a part of the top of the table.
8. A table provided with a frame having guides, sliding leaves having extensions mounted in said guides, folding leaves hinged 110 to the frame and a depressible center movably mounted within the frame.
9. A table provided with a frame having guides, sliding leaves having extensions mounted in said guides and being constructed 115 to abut over the frame, folding leaves hinged to the frame and constructed to fold within the same below the sliding leaves and a depressible center movable within the frame and abutting against said sliding and folding leaves when in operative position. 120
- In testimony whereof I have signed my name to this specification in the presence of two subscribing witnesses.

CHARLES E. WEHN.
